UNITED STATES PATENT OFFICE.

FRANK CRAIGIE AND JOHN HINES, OF CHICAGO, ILLINOIS.

NOZZLE.

1,351,840.

Specification of Letters Patent.

Patented Sept. 7, 1920.

Application filed May 3, 1919. Serial No. 234,540.

To all whom it may concern:

Be it known that we, FRANK CRAIGIE and JOHN HINES, citizens of the United States, residing at Chicago, county of Cook, and 5 State of Illinois, have invented certain new and useful Improvements in Nozzles, of which the following is a specification.

This invention relates to improvements in spray nozzles.

10 An object of the invention is to provide a device whereby jets of liquid may be discharged from a nozzle in the form of a fine spray or mist.

It is also an object of the invention to 15 effect the discharge of the liquid in finely divided form through means which cause a deflection of the liquid from that direction in which it flows through the nozzle, and to force the liquid under pressure through a

20 path in which it is subjected to the action of centrifugal force prior to its complete discharge.

It is also an object of the invention to provide a device of this character particularly 25 adapted for saturating air with moisture by discharging the spray from the device in the form of a large cone spreading from the point of discharge outwardly.

With these and other objects in view, the 30 preferred embodiment of the invention is described in the following specification and illustrated in the accompanying drawing, wherein—

Figure 1 is a side elevation of the complete device;

Fig. 2 is a central longitudinal section through the stem;

Fig. 3 is a front view of a nozzle head plate;

40 Fig. 4 is a side elevation of the nozzle head, and

Fig. 5 shows a front elevation and section 45 respectively of the means for deflecting the stream emanating from the nozzle head from its path for the discharge through the nozzle cap.

The device comprises a nozzle head 1, which consists of a stem 2 and a nozzle head plate 3. The stem may be provided with 50 ordinary tapering pipe thread 4 for attachment to a suitable conduit for the liquid, and adjacent to said threaded portion it has a hexagonal portion 5 to facilitate the attachment of the nozzle head by means of a wrench or other tool to the conduit. A

55 tapering passage 6 extends axially through

the stem 2 of the nozzle head 1, opening at its narrower end in the front surface of the stem.

The stem is integral with the nozzle head 60 plate 3, which is preferably circular, as shown in Fig. 3, and which is located in a plane perpendicular to the axis of the stem. The front portion of the head plate 3 has external threads for the attachment of a nozzle 65 cap. This circular plate 3, while being integral with the stem 2 of the nozzle head, is eccentric to the same, and readily detachable means are provided for deflecting the stream of water discharged from the passage 70 70 on the outer surface of the plate 3 in a direction in which this stream will be gradually deflected toward the center portion of the head plate 3.

These deflecting means, in the present instance, comprise a disk 7, having a cut-out portion in the form of a spiral 8, the outer end of which, as indicated at 9, will overlie, when placed in operative position, the discharge opening of the passage 6, 80 while the inner end of the spiral, as indicated at 10, will overlie the central portion of the head plate 3, which central portion, as stated above, is located eccentrically with respect to the opening through which the 85 liquid flows in the nozzle head. The head plate 3 is provided with sockets 11, which serve for receiving the pins 12, projecting from the lower side of the deflecting plate 7, whereby said deflecting plate may readily 90 be secured to the front surface of the head plate or may be detached therefrom when desired.

This deflecting plate also is located in a plane at right angles to the direction of flow 95 of the liquid, and is covered by a nozzle cap 13, having an internal thread or tapped portion whereby it can be attached to the margin of the head plate 3. The central portion of the cap, as shown in Figs. 1 and 2, is 100 raised in opposition to the central portion of the head plate 3, whereby a conical or concave chamber 14 is provided. This chamber 14 communicates with a flaring central discharge opening 15 in the raised 105 portion of the cap.

All of the parts preferably are made of bronze or some other metal which will not be affected by contact with liquids.

It will be seen from the above that the 110 liquid, after having flowed in axial direction through the nozzle head 1, is deflected

from this path and is confined in the spiral path between the portions 9 and 10 of the spiral plate 7, so as to flow in a plane at right angles to the axis of the passage 6. 5 Owing to the contact of the deflecting means 7 with the surface of the head plate 3 and with the inner surface of the nozzle cap 13 respectively, the liquid is forced to flow in this spiral reduced path at great speed, 10 entering suddenly the enlarged chamber 10, which is in communication with the concavity 14 of the nozzle cap, from which the liquid then is discharged in a direction parallel to the direction of initial flow through 15 the flared opening 15 of the cap. As the liquid is conveyed under sufficient pressure and with great speed through this spiral path, it is subjected to the action of centrifugal force, and in its discharge is broken 20 up into a finely divided spray.

An important feature of the invention also is that the passages leading from the opening of the passage 6 to the discharge opening 15 are relatively large, so that there 25 is very little danger of having these passages clogged up between the free end of the opening 6 and the discharge opening 15. If, however, it is a solid body, the nozzle cap 13 can readily be removed and the spiral passage can readily 30 be cleaned or another deflecting plate 7 may 35 be put in place.

We claim:

1. In a device of the character described, the combination of a nozzle having a tapering axial passage therethrough, said nozzle 40 including a head plate, a plate having a spiral cut-out secured to said head plate, and a nozzle cap in opposition to said head plate and secured thereto, said plate with the spiral cut-out being located on said head 45 plate in a position in which one end of the spiral cut-out communicates with the discharge opening of the axial passage, while the other end of the spiral cut-out is in opposition to the central portion of the nozzle 50 cap, said nozzle cap being provided in its central portion with a cavity and a discharge opening in said cavity.

2. In a device of the character described, the combination of a nozzle head having a nozzle stem and a circular head plate, the 55 nozzle stem having an axial passage therethrough and the center of the circular head plate being disposed eccentrically with respect to said axial passage, a spiral deflecting means mounted on said head plate and 60 adapted to convey the liquid discharge from the passage toward the center of said head plate, and a nozzle cap secured to said head plate and having a discharge opening in opposition to the center of said head plate. 65

3. In a device of the character described, the combination of a nozzle having an axial passage therethrough and having a circular head plate with its center disposed eccentrically to said passage, a plate having a 70 single spiral cut-out portion detachably mounted on said circular head plate, the outer end of said cut-out portion overlying the center of said circular head plate, and a nozzle cap removably mounted on said circular head plate having a concave chamber in opposition to the inner end of said deflecting spiral and having an outwardly flaring discharge opening communicating with said chamber. 75

4. In a device of the character described, the combination of a nozzle having an axial tapering passage therethrough, a circular head plate integral with said nozzle and having its center eccentric with respect to 85 said passage and in a plane at right angles to the axis of said passage, a nozzle cap having a central chamber on its inner surface and an outwardly flaring discharge opening communicating with said chamber, said 90 nozzle cap being secured to said circular head plate, and a spiral deflector confined between said head plate and said nozzle cap, and adapted to deflect the liquid discharged from said axial passage in a spiral 95 path toward the chamber of said nozzle cap.

In testimony whereof we affix our signatures in the presence of two witnesses.

FRANK CRAIGIE.
JOHN HINES.
